UNITED STATES PATENT OFFICE

DONALD G. SMELLIE, OF CANTON, OHIO, ASSIGNOR TO THE HOOVER COMPANY, OF
NORTH CANTON, OHIO, A CORPORATION OF OHIO

SUCTION CLEANER

Application filed December 1, 1930. Serial No. 499,135.

The present invention relates to suction cleaners and particularly to improvements therein designed to increase the cleaning efficiency of the cleaner in which they are incorporated. More specifically the invention relates to an improved suction cleaner in which the construction is so modified as to direct the cleaning air entering the nozzle to substantially the point of maximum surface covering agitation and further directs the same cleaning air under surface-contacting lips of a type which assist the air in its dirt-removing function. The invention also includes the provision of means to increase the velocity of the cleaning air as it passes under the surface-contacting lips.

It is an object of the present invention to provide a suction cleaner of increased cleaning efficiency. It is a further object to provide a suction cleaner in which the cleaning air enters the nozzle proper at substantially the point of maximum surface covering agitation. It is another object to provide a suction cleaner nozzle construction which contains cleaning fluid at different pressures and in which the flow of fluid from the point of high pressure to the point of low pressure is past a point of surface covering agitation. It is still another object to provide in a suction cleaner a novel arrangement of parts in which a rotary agitator is positioned within a body of fluid at substantially air pressure which is surrounded by a second body of fluid at a reduced pressure and in which the point at which the agitator contacts the surface covering undergoing cleaning is closely adjacent the point at which the cleaning fluid passes from the body of high pressure to the body of low pressure in the operation of the machine. A still further object is the provision of a suction cleaner construction characterized by the presence, within the suction nozzle, of a body of air at greater than atmospheric pressure and a body of air at less than atmospheric pressure; and by the further fact that the flow of air from the point of high pressure to the point of low pressure is past a point of surface covering agitation. It is a still further object of the present invention to provide a new and novel

suction cleaner nozzle construction. Other and more specific objects will appear upon reading the following specification and considering therewith the drawings which are related thereto.

Referring now to the drawings in which preferred embodiments of the present invention are disclosed and in which like reference characters refer to the same parts throughout:

Fig. 1 is a side view of a suction cleaner embodying the present invention with certain parts broken away and in section;

Fig. 2 is a top view of the machine shown in Fig. 1 with certain parts broken away and shown in section upon the line 2—2 of Fig. 1;

Fig. 3 is a front view of the suction cleaner embodying the present invention with the front wall of the nozzle broken away and showing certain parts in section;

Fig. 4 is a section upon the line 4—4 of Fig. 3;

Fig. 5 is a section upon the line 5—5 of Fig. 3 with the agitator and air tunnel removed;

Fig. 6 is a section upon the line 6—6 of Fig. 5;

Fig. 7 is a partial view upon the line 7—7 of Fig. 2 showing the power transmission from the motor shaft to the agitator driving pulley;

Fig. 8 is a front view upon a section thru the nozzle of a modified embodiment of the present invention;

Fig. 9 is a view similar to Fig. 8 of a further modification;

Fig. 10 is a longitudinal section thru the nozzle of a modified form of the present invention;

Fig. 11 is a section upon the line 11—11 of Fig. 10;

Fig. 12 is a view in perspective of the improved agitator embodied in the modification of the present invention shown in Figs. 10 and 11;

Fig. 13 is a further form of agitator that can be embodied in the modification shown in Figs. 10 and 11.

In the drawings, and in Figures 1 to 7 in particular, a suction cleaner embodying the

55

60

70

75

80

95

100

present invention is disclosed and comprises a main casting or casing 10 which forms the cleaner nozzle 11, which includes the front and rear walls 12 and 13 respectively; the fan 5 chamber 14, and the exhaust outlet 15 which is adapted to receive a suitable dust bag or dirt separator. A motor, casing 16, which houses a suitable driving motor, is positioned upon the main casing 10 immediately above the fan 10 chamber 14, and motor shaft 17, projects downwardly therefrom into the fan chamber 14 where the suction-creating fan 18 is mounted thereon. The bottom plate 19 of the motor casing supports the lower bearing 20 for the 15 motor shaft 17 and also provides the upper wall of the air passage from the suction nozzle 11 to the eye 21 of the fan chamber 14 which is formed in the upper wall 22 thereof. A depending curved wall 23 on the motor 20 bottom plate 19 cooperates with the upper wall 22 of the fan chamber to form the sides and bottom of the air directive passage leading to the eye. The entire construction is 25 movably supported upon the surface undergoing cleaning by means of the front supporting wheels 24, 24 positioned in the wheel pockets formed by casing 10 immediately adjacent the nozzle 11, and the rear supporting wheel 25, as in the usual suction cleaner.

30 Positioned within the suction nozzle 11 is an agitator 26 of a common and well known type which is rotatably supported upon the non-rotatable shaft 27 which is itself supported at its ends in the end walls 35, 35 of 35 the nozzle 11. The agitator 26 is adapted to be rotated at high speed while in contact with the surface covering undergoing cleaning and imparts thereto a distinct and positive agitation as the rigid beaters 28, 28 and the flexible 40 brush 29 contact therewith. The agitator 26 is positioned midway of the nozzle 11 between the walls 12 and 13 and extends substantially into the plane of the broad-sealing lips 30 and 31 carried by said nozzle.

45 On one end of the agitator is secured, by means of supports 33, 33, a pulley 32 which is positioned outside the interior proper of the nozzle, that is that part which is directly connected to the fan chamber, within a 50 separate compartment or housing formed by the vertical wall 34 which extends parallel to the nozzle end walls. At the rear of this separate compartment, or pulley housing, is a second pulley 36 which is carried by a transversely-extending rotatable shaft 37 mounted in bearings 38 and 39 carried by the fan 55 chamber 14 and the depending wall 34 respectively. The shaft 37 extends from the pulley 36 to a well 40, see Figures 1 and 7, 60 formed in the bottom of the fan chamber 14 by a circular wall and by a removable cover 41, which encloses in sealed relationship, as indicated at 42, the lower extremity of the motor shaft 17. Within the well 40 is rotatably mounted a worm gear 43 which is driven 65 by the shaft 17 and which makes driving contact with a spiral gear 44 carried at the end of the shaft 37. The rotation of the motor shaft 17 functions to rotate the shaft 37, through the intermeshing gears 43 and 44, 70 which rotates the pulley 36, and the power is transmitted thru a belt 45 to the pulley 32 carried by the rotatable agitator for the purpose of rotating said agitator.

75 Positioned within the nozzle 11 and enclosing the agitator 26 is a housing or air tunnel 46, the lower or under surface of which is provided with an opening or slot defined by longitudinally extending parallel lips 47 and 48 respectively which are in all 80 respects surface-contacting lips of a type known as pile penetrating, being relatively thin as compared to the usual nozzle lips and of such thickness as to be able to extend between adjacent tufts of pile and into a single tuft of pile. Tunnel 46 is maintained in nozzle 11 by means of the removable seats at its opposite ends which are indicated by the reference characters 50, 50, see Figures 5 and 6. These seats 50, 50 are held in place 85 relative to the end wall 35 and the depending wall 34, at the opposite ends of the air tunnel 46, by suitable means such as screws 51, 51 and when in place function to support the ends of the tunnel and to clamp them against 90 the overhanging circular walls or flanges 52, 52 formed on the opposed end wall and depending wall. For the purpose of making the clamping action more positive the seats 50, 50 are provided with shoulders 53, 53 95 which cooperate with the notched ends 54, 54 of tunnel 46, see Figure 3.

100 Within the nozzle 11 between the front and rear walls thereof are spaced walls 55, 55 which extend downwardly and outwardly and which encircle the opposite upper ends of the tunnel 46 sealing them from the remainder of the interior of the nozzle in substantially air tight relationship. Within the surface areas of the tunnel defined by the lines of contact of the walls 55, 55 are provided openings 56, 56 which connect the interior of the tunnel with those portions or pockets in the nozzle which are sealed from the interior proper thereof by the walls 55, 55. The rear wall 13 of the nozzle 11 at its 105 ends, and adjacent the pockets defined by the walls 55, 55, is provided with openings 57, 57 of substantially the same area as the openings 56, 56 in the tunnel 46. The presence 110 of openings 57, 57 in wall 13 provides means of direct communication between the interior of the air tunnel 46 and the air at atmospheric pressure exterior of the machine and as found within the wheel pockets 115 formed by casing 10 which contain the front supporting wheels 24, 24 immediately adjacent the rear nozzle wall 13. It is understood that the presence of the walls 55, 55 serves 120 to prevent the passage of the air entering 125 130

the nozzle pockets through the openings 57, 57 to any part of the interior of the nozzle except to the interior of the air tunnel 46 thru the openings 56, 56.

5 In the operation of the cleaner constructed in accordance with the aforescribed embodiment of the present invention as the motor revolves the suction-creating fan creates a reduced pressure within the nozzle 11 in 10 that portion exterior of the air tunnel 46 and between the walls 55, 55. The presence of the reduced pressure within the nozzle lifts the surface covering undergoing cleaning up into contact with the broad sealing 15 lips 30 and 31 which, because of their relatively great width, serve to materially reduce the flow of air between themselves and the said surface covering. With the flow of air under the nozzle lip 30 and 31 reduced to 20 a substantially negligible quantity, practically all the air entering the nozzle enters through the air tunnel 46, having gained entrance thereto through the openings 56, 56 which connect, as aforescribed, to the openings 25 57, 57 in the rear wall 13 which are open to the atmospheric air. In gaining entrance to the interior of the nozzle from tunnel 46, with the surface covering raised by the nozzle suction, the cleaning air must pass under the 30 penetrating lips 47 and 48 of the tunnel 46 which are extended into said covering and between the tufts of pile thereof. With the penetrating lips 47 and 48 positioned relatively close together and with the agitator 35 positioned between them the point of air cleaning effectiveness is spaced but a short distance from the point of maximum agitation as represented by the point of contact of the revolving agitator 26 and the surface 40 covering with a desirable increase in cleaning efficiency resulting from such relationship.

The construction of the aforescribed invention is one of relative simplicity and involves no complicated mechanism to accomplish its purpose. The construction is easily disassembled, it being necessary only to remove one of the end plates 35, which is made detachable for that purpose, as indicated at 45 50 55 60 65 70 75 80 85 90 95 100 105 110 115 120 125 130

Referring now to Figures 8 and 9, further embodiments of the present invention are disclosed. Use has been made of what are known as small diameter agitators, having different characteristics than the agitator embodied in the first described modification and the dimensions of the cleaner have been 60 slightly altered to accommodate the change in agitators.

Referring to Figure 8, in particular, the suction cleaner is shown and comprises, as in the previous embodiment, the nozzle 11, 65 which forms part of the main casing 10, the

motor casing 16 and the front supporting wheels 24, 24. The air tunnel, which is indicated by the reference character 46, is suitably positioned within the nozzle 11 and secured, as in the previous embodiment, and is provided at its ends with the openings 56, 56 which open into the pockets formed in the ends of the nozzle by the downwardly and outwardly extending walls 55, 55. The rear wall 13 of the nozzle 11 is provided with 70 75 80 85 90 95 100 105 110 115 120 125 130

Referring now to the agitator which is indicated generally by the reference character 70, it is noted that the agitator is of relatively small diameter, and that instead of having beating elements upon its surface it is provided with surface contacting helical elements, indicated by the reference characters 71, 71, which are relatively thin and which are positioned on the agitator body in the manner of screw threads. The agitating elements, 71, 71 lie upon the surface of the agitator 70 upon a very small pitch and upon the rotation of agitator 70 function rather as pile separators and deflectors than as beaters as do the elements 28, 28 of the agitator in the first described embodiment of the present invention. The elements 71, 71 are shown as extending in opposite directions with reverse angularity from a common point 72 at substantially the center of the agitator.

Between the successive turns of the helical pile-deflecting elements 71, 71 extend brushes suitably carried by the agitator 70 and which are indicated by the reference characters 73, 73. Brushes 73, 73 have a common central point 74 which is spaced circumferentially from the common point 72 of the pile-deflecting elements 71, 71. At one of its ends, and outside the downwardly-extending wall 34 in the nozzle, the agitator carries a pulley 75 which is threaded upon, and so rigidly carried by, the threaded end 76 of the agitator 70. Both agitator 70 and pulley 75 are rotatably mounted upon the stationary non-rotatable shaft 77 which is suitably mounted at its ends within the end walls 35, 35 of the nozzle 11. As in the previous embodiment the agitator is rotated by the belt 45 which receives its power thru the transmission mechanism described in connection with the previous embodiment.

The present modification functions, in its broad aspects, substantially as does the aforescribed embodiment but differs therefrom in the agitation which is given to the surface covering undergoing cleaning by the agitator. In the operation of the present machine the agitator 70 revolves at a high speed between the lips of the air tunnel 46, 46 but, instead of positively beating and sweeping

the surface covering, as was the case in the previous embodiment, the surface covering pile is deflected and separated by the rotation of the screw-like pile-deflectors 71, 71 which, 5 because of their relatively small pitch perform substantially no beating function, but instead wedge themselves into and thru the pile and deflect it to the sides. The rotating brush elements 73, 73 function to brush the 10 surface covering after the pile-deflecting elements have passed thereover. As in the previous embodiment the point of maximum surface covering agitation, as represented by the point of contact of the agitator and the 15 surface covering, is closely adjacent the point at which the air leaves the tunnel 46 and enters the nozzle 11, this latter point being under the lips of the tunnel 46, as shown in Figures 1 and 4 in particular. Because of the relatively 20 small diameter of the agitator in the present modification, the lips of the tunnel can more closely approach the point of surface covering agitation with a resultant increased cleaning efficiency.

25 Referring now to Figure 9 in particular a still further modification of the present invention is disclosed which is quite similar to that shown in Figure 8, being of the small-diameter agitator type, but differs therefrom 30 in the specific type of agitator used. In the present embodiment the agitator, which is indicated by the reference character 80, is provided with a corrugated surface which comprises alternate raised and lowered portions 35 which extend helically. At substantially the center of the agitator the direction of angular advance is reversed so that the pile-deflectors, which are formed by the raised portions on the surface of the agitator body 40 and which are represented by the reference character 81, extend in opposite directions of angular advance from the mid-point of the agitator. As in the previous modifications the pile-deflecting elements are of relatively 45 small pitch and function, not as surface covering beaters, but instead as pile-deflectors which comb and deflect the pile of the surface covering. Superimposed upon the surface of the agitator 80, and extending radially 50 a substantial distance beyond the raised portions 81, 81, are the beater elements 82, 82 which are of the common and well known positive beater type. Elements 82, 82 extend in opposite directions of angular advance 55 from midpoint of the agitator and each element 82 advances in the opposite direction from the pile-deflecting element 81 on which it is superimposed. Agitator 80 carries a pulley 85, at one of its ends outside the depending wall 34, which is secured to the agitator by screws 86, 86. Agitator 80 is rotatably mounted upon a supporting shaft 87 as in the first embodiment.

60 In the operation of this last described embodiment of the present invention the sur-

face covering is agitated both by the pile-deflection of the elements 81, 81 and by the positive beating, in the sense of vertical displacement, of the elements 82, 82. As in the previous embodiments the point at which the cleaning air leaves the air tunnel 46 to enter the main nozzle 11, and in so doing contacts the surface covering, is closely adjacent to the point of surface covering contact by the agitator.

65 As disclosed in Figures 10 to 13 inclusive, the present invention incorporates means for increasing the cleaning efficiency of the machine through increasing the velocity at which the air passes under the lips of the air tunnel in gaining entrance to the suction nozzle; it being recognized that cleaning efficiency varies with the velocity of the air which contacts the covering and removes the embodied foreign matter. This is accomplished by means of raising the pressure within the air tunnel to a pressure greater than atmospheric.

70 In the drawings, and in Figures 10, 11 and 12 in particular, reference character 11 again represents the suction cleaner nozzle which is provided with the end plates 35, 35 and at one end with a depending wall 34. The air tunnel 46 extends between one end wall 35 and the depending wall 34 and is unprovided with cut-away portions at its ends, as in the previous embodiments, but instead extends continuously between the limits mentioned. According to the present embodiment the cleaning air gains entrance to the air tunnel 75 at the ends through openings in the end walls 35, 35 which are indicated by the reference characters 90, 90. The agitator proper is represented generally by the character 91 and is of a common and well known type being provided with helically extending beater bars, one of which is indicated by 92, and longitudinally extending brushes 93, 93. At the opposite ends of the agitator, however, are provided radially and inwardly extending blades 94, 94 etc. between which the surface of agitator 91 is provided with openings as indicated by the reference characters 95, 95 etc. At its ends agitator 91 is provided with end plates, as indicated by 96, 96, which are open as at 97 over a large part of their area. Each end plate 96 is provided with a longitudinally extending cylindrical portion 98 within which bearings, indicated generally by the reference characters 99, 99, are seated and which serve to rotatably support the agitator upon the non-rotating shaft 100 which is carried by the end plates 35, 35 of the nozzle 11. The agitator of the present modification receives its rotating force, as in all the previous exemplifications, by means of a pulley, which is indicated by the reference character 101, which is carried between the end wall 35 and the depending wall 34 by the agitator, being connected thereto as by suit-

able screws 102 which extend into the end plate 96 of the agitator. The pulley is provided with longitudinally-extending opening 103 which are aligned with the openings 97 in the adjacent end plate 96 in order that the cleaning air may gain entrance to the agitator from the openings 90 in the nozzle end wall. A belt 45, which is driven as described in a previous modification, is operatively connected to the pulley.

In the operation of the machine embodying the instant modification of the present invention upon the rotation of the agitator 91 the surface covering is positively agitated and swept between the front and rear lips 47 and 48 of the air tunnel 46, into contact with which it is drawn by the suction existing within the nozzle 11. The rotation at high speed of the blades 94, 94 etc. at each end of the agitator causes those blades to act as a centrifugal fan functioning to draw air into the agitator thru the ends and forcing it outwardly thru the opening 95, 95 etc., into the air tunnel. The air exhausted from the agitator is received in the air tunnel 46 and there builds up a positive pressure which is greater than atmospheric, to an extent dependent upon the effectiveness of the afore-described fan. As in the previous modifications air within the air tunnel enters the surrounding nozzle by passing under the air tunnel lips 47 and 48 which are of the pile penetrating type. In the present modification it is clear that the velocity of the air passing under said lips into the nozzle is increased because of the greater pressure difference existing between the interior of the air tunnel and the surrounding nozzle.

In Fig. 13 an agitator shell with the end plates removed is shown which is applicable in the modification of the present invention which is shown in Figs. 10 and 11. The present form of agitator differs from that described and shown in Figure 12 in that the blades 94 and the opening 95 between said blades extend the entire length of the agitator instead of being positioned only at the ends thereof. In an agitator so constructed the pressure in the air tunnel 46 can be raised to a greater extent than would be possible with the agitator constructed as disclosed in Figure 12. The beating and sweeping function of the agitator, as performed by the positive beaters and the brushes, is in no way changed.

Having clearly disclosed and claimed the present invention and several of its desirable and preferred embodiments, I claim:—

1. In a suction cleaner a suction nozzle, means to draw air through said nozzle, a housing in said nozzle in communication with the exterior atmosphere and open to said nozzle on its under side and a pile penetrating lip adapted to extend between adja-

cent tufts and into a single tuft of pile formed thereon.

2. In a suction cleaner a suction nozzle, means to draw air through said nozzle, a longitudinally-extending housing in said nozzle in communication with the exterior atmosphere and having a longitudinal opening on its lower side, and pile-penetrating lips of such thickness as to be able to extend between adjacent tufts of pile and into a single tuft of pile formed on said housing adjacent the sides of said opening.

3. In a suction cleaner, a casing including a nozzle, surface-contacting lips defining the mouth of said nozzle, means movably supporting said casing with said lips spaced above a surface covering, suction-creating means connected to and adapted to create a reduced pressure in said nozzle to effect the lifting of said surface covering into contact with said lips and into said mouth between said lips, an air tunnel in said nozzle interiorly connected to atmosphere and to said nozzle and adapted to convey air into said nozzle in response to a reduced pressure existing therein, and surface-contacting means adapted to contact the portion of the lifted surface covering in said nozzle mouth and defining the opening of said air tunnel into said nozzle.

4. In a suction cleaner, a casing including a nozzle, surface-contacting lips defining the mouth of said nozzle, means movably supporting said casing with said lips spaced above a surface covering, suction-creating means connected to and adapted to create a reduced pressure in said nozzle to effect the lifting of said surface covering into contact with said lips and into said mouth between said lips, an air tunnel in said nozzle interiorly connected to atmosphere and to said nozzle and adapted to convey air into said nozzle in response to a reduced pressure existing therein, and surface-contacting pile penetrating lips adapted to contact the portion of the lifted surface covering in said nozzle mouth and defining the opening of said air tunnel into said nozzle.

5. In a suction cleaner a suction nozzle, means to draw air through said nozzle, a housing in said nozzle in communication with the exterior atmosphere and open to said nozzle in substantially the plane of surface contact and a surface covering agitator positioned in said housing.

6. In a suction cleaner a suction nozzle, means to draw air through said nozzle, a housing in said nozzle in communication with the exterior atmosphere and open to said nozzle in substantially the plane of surface contact, and a rotary agitator positioned in said housing and arranged to contact the surface covering undergoing cleaning.

7. In a suction cleaner a fan chamber, a suction-creating fan in said chamber, a driv-

ing motor connected to said fan, a suction nozzle directly connected to said fan chamber, lips upon said nozzle, a rotary agitator in said nozzle, power transmission means connecting said agitator to said driving motor, a housing open to the exterior atmosphere enclosing said agitator and provided with a longitudinal opening and lips carried by said housing adjacent said opening and substantially in the plane of said nozzle lips.

8. In a suction cleaner, a fan chamber, a suction-creating fan in said chamber, a driving motor connected to said fan, a suction nozzle directly connected to said fan chamber, lips upon said nozzle defining the nozzle mouth, a rotary agitator in said nozzle, power transmission means connecting said agitator to said driving motor, a housing within said nozzle enclosing said agitator and provided with an opening substantially in the plane of said nozzle lips, a depending and outwardly extending wall in said nozzle closely enclosing an end portion of said housing at the top and sealing said portion from the mouth of said nozzle, said housing being formed with an inlet-opening in that portion sealed from the nozzle mouth, and the rear wall of said nozzle being provided with an opening connecting the inlet-opening of said housing to the exterior atmosphere.

9. In a suction cleaner a suction nozzle, means to draw air through said nozzle, a housing in said nozzle in communication with the exterior atmosphere and open to said nozzle in substantially the plane of surface contact, and beating and sweeping means positioned in said housing and arranged to contact the surface covering undergoing cleaning.

10. In combination in a suction cleaner having a suction nozzle, stationary agitating means within said nozzle, means to direct the flow of cleaning air entering said nozzle under said stationary agitating means, and additional positively actuated agitating means in said nozzle.

11. In a suction cleaner, a casing including a nozzle, surface-contacting lips defining the mouth of said nozzle, means movably supporting said casing with said lips spaced above a surface covering, suction-creating means connected to and adapted to create a reduced pressure in said nozzle to effect the lifting of said surface covering into contact with said lips and into said mouth between said lips, positively actuated surface covering pile-deflecting means in said nozzle adapted to contact the portion of the lifted covering in said nozzle mouth, and an air tunnel interiorly connected to atmosphere and open to said nozzle for the purpose of directing cleaning air into the deflected pile of the surface covering undergoing cleaning.

12. In a suction cleaner a suction nozzle, means to draw air through said nozzle, a

housing in said nozzle in communication with the exterior atmosphere and open to said nozzle in substantially the plane of the nozzle lips, and positively actuated surface covering pile-deflecting means positioned in said housing comprising a rotary agitator having small-pitch spiral extensions upon the surface thereof.

13. In a suction cleaner a suction nozzle, means to draw air through said nozzle, a housing in said nozzle in communication with the exterior atmosphere and open to said nozzle in substantially the plane of the nozzle lips, and positively actuated surface covering pile-deflecting and positive-beating means positioned in said housing comprising a rotary agitator having small-pitch spiral extensions forming deflecting elements and large-pitch spiral extensions forming beating elements.

14. In a suction cleaner, a casing including a nozzle, surface-contacting lips defining the mouth of said nozzle, means movably supporting said casing with said lips spaced above a surface covering, suction-creating means connected to and adapted to create a reduced pressure in said nozzle to effect the lifting of said surface covering into contact with said lips and into said mouth between said lips, an air tunnel in said nozzle interiorly connected to atmosphere and to said nozzle and adapted to convey air into said nozzle in response to a reduced pressure existing therein, surface-contacting means adapted to contact the portion of the lifted surface covering in said nozzle mouth and defining the opening of said air tunnel into said nozzle, and means in said tunnel to increase the pressure therein above the atmosphere to increase the velocity of air flow from said tunnel into said nozzle.

15. In a suction cleaner a suction nozzle having lips adapted to contact a surface covering undergoing cleaning, means to create a reduced pressure in said nozzle, a housing in said nozzle connected to atmosphere and open to said nozzle in substantially the plane of the lips thereof, surface-contacting members on said housing defining the opening therein, a rotary agitator in said housing arranged to contact the surface covering between the surface-contacting members thereon, and means to increase the pressure in said housing above the atmosphere to increase the velocity of air flow from said housing into the nozzle under said surface-contacting members comprising a centrifugal fan formed in said agitator open to said housing at its high pressure point.

16. A suction cleaner comprising a suction nozzle, spaced surface-contacting lips defining the nozzle mouth, means to create a reduced pressure in said nozzle and to draw air therefrom, an air tunnel in said nozzle open thereto in substantially the plane of the

nozzle mouth, an open-ended hollow rotary agitator mounted in said air tunnel and interiorly connected to the external atmosphere through the surrounding nozzle, and a

5 centrifugal fan formed in said agitator open to and exhausting in said air tunnel to increase the pressure therein for the purpose of increasing the velocity of the air flow from said tunnel opening into said nozzle.

10 17. A suction cleaner comprising a nozzle, suction-creating means connected to said nozzle, broad-sealing lips on said nozzle adapted to contact the surface covering undergoing cleaning and substantially prevent the

15 flow of air therebetween into said nozzle, and an air tunnel positioned in said nozzle connected interiorly to the external atmosphere and open to said nozzle in substantially the plane of the lips thereof, pile-penetrating lips carried by said tunnel defining the sides of the opening therein and adapted to contact the surface covering, and means to increase the pressure in said tunnel for

20 the purpose of increasing the velocity of air flow under said penetrating lips into the nozzle.

18. A suction cleaner comprising a nozzle, suction-creating means connected to said nozzle, broad-sealing lips on said nozzle adapt-

30 ed to contact the surface covering undergoing cleaning and substantially prevent the flow of air therebetween into said nozzle, and an air tunnel positioned in said nozzle connected interiorly to the external atmosphere

35 and open to said nozzle in substantially the plane of the lips thereof, pile-penetrating lips carried by said tunnel defining the sides of the opening therein and adapted to contact the surface covering and means posi-

40 tioned in said tunnel to increase the pressure therein for the purpose of increasing the velocity of an air flow under said penetrat-

ing lips into said nozzle.

19. In a suction cleaner, a suction nozzle

45 having lips adapted to contact a surface covering undergoing cleaning, means to create a reduced pressure in said nozzle, a housing in said nozzle, means to create a positive pressure in part of said housing, said hous-

50 ing being open to atmosphere at its point of low pressure and to the nozzle at its point of high pressure, and a surface-contacting

lip on said housing defining one side of the

55 opening to said nozzle.

20. In a suction cleaner, a suction nozzle, a housing in said nozzle open to said nozzle and interiorly connected exteriorly thereof, an agitator in said housing, and means to produce a positive pressure in said housing.

60 21. In a suction cleaner, a suction nozzle, broad-sealing lips carried by said nozzle, means to draw air through said nozzle, an air tunnel in said nozzle in communication

65 with the exterior atmosphere, and spaced surface - contacting pile - penetrating lips

adapted to extend between adjacent tufts of pile on said tunnel defining an opening into said nozzle in substantially the plane of the broad sealing lips.

22. In a suction cleaner, a casing includ-
ing a nozzle, surface-contacting lips defin-
ing the mouth of said nozzle, means movably
supporting said casing with said lips spaced
above a surface covering, suction-creating
means connected to and adapted to create
a reduced pressure in said nozzle to effect
the lifting of said surface covering into con-
tact with said lips and into said mouth be-
tween said lips, an elongated air tunnel in
said nozzle interiorly connected thru top
openings at its ends thru said nozzle to at-
mosphere and open to said nozzle thru an
opening along its underside, and surface-
contacting means adapted to contact the por-
tion of the lifted surface covering in said
nozzle mouth and defining the sides of the
opening of said air tunnel into said nozzle.

Signed at North Canton, in the county of Stark and State of Ohio, this 26th day of November, A. D. 1930.

DONALD G. SMELLIE.
